Atty's.

UNITED STATES PATENT OFFICE.

JAMES MILTON ENGLISH, OF ALLIANCE, OHIO.

STOPPER FOR BOTTOM-POUR LADLES.

1,303,548.

Specification of Letters Patent.

Patented May 13, 1919.

Application filed January 23, 1919. Serial No. 272,732.

To all whom it may concern:

Be it known that I, JAMES MILTON ENGLISH, a citizen of the United States, resident of Alliance, Ohio, have invented certain new and useful Improvements in Stoppers for Bottom-Pour Ladles, of which the following is a specification.

My invention relates to a stopper for bottom pour ladles used to contain molten metal and is designed to provide a connection for the stopper and a support for the tile protecting the rod from the action of the molten metal which is utilized to lift the stopper.

15 In the accompanying drawing:

Figure 1 shows an elevation of a ladle partly in section with my invention applied thereto, while Fig. 2 is a detail sectional view showing the specific improvement.

20 Fig. 3 is an elevation of a part of the ladle showing the operating means for the stop.

The ladle is shown at A and the stopper which is of black lead is shown at B, closing the discharge opening from the ladle. A 25 rod C is detachably connected to the stopper by a bayonet joint and after given a quarter turn the usual space is filled in with a suitable packing, this construction being usual and well known. The stopper rod 30 has projections a on each side above the lower end so as to support the protecting tiling b around the rod, this tiling being in sections as shown in Fig. 1 and extending to the top of the ladle above the level of the 35 molten metal within the same. The rod has a goose neck d which has an adjustable connection of usual construction with the side of the ladle so that it can be readily raised and lowered to open or close the discharge 40 nozzle.

It frequently happens that a disconnection occurs between the stopper and the stopper rod and the tiling is usually lost in such a case, as it is generally supported by 45 the stopper, but by being independently supported, as in the construction shown, it moves with the stopper rod and is wholly independent of the stopper and the sections of tiling may be replaced as may be found 50 desirable.

The adjustment of the stopper rod is effected through a support on the ladle sustaining a vertically movable plate slotted which is actuated by a lever to raise and lower the same.

The lower end of the rod C is reduced where it receives the stopper B and this lower end has spaced apart flanges or ribs a' and these are in the same radial planes with the flanges or ribs a, at the lower end of the 60 full diameter portion of the rod C so that the spaces between the circumferential flanges a overlie the spaces between the lower flanges a' and the rod adjacent the flanges a and for some distance above the plane of these flanges 65 is recessed, the bottoms of these recesses c' being coincident with the side face of the reduced end of the rod. This construction provides for a bayonet joint fitting of the stopper B to the lower end of the rod and 70 while providing for supporting the tile on the flanges a provision is made by spacing these flanges apart and by forming the recesses in the rod between and above them for introducing the packing material into the 75 spaces of the stopper, resulting from the bayonet joint connection.

What I claim is:

A stopper device for bottom pour ladles comprising a rod having its lower portion 80 of reduced diameter to receive the stopper, said reduced portion having flanges spaced apart from each other and extending in a direction circumferentially of the rod, flanges spaced apart at the lower end of 85 the full diameter portion of the rod, said flanges being in the same radial planes with the lower flanges and said rod having recesses extending between and above the upper flanges and with their bottoms substantially coincident with the side face of the reduced diameter portion of the rod and tiling supported on the upper flanges, all of said flanges being integral with the rod, substantially as described.

95 In testimony whereof I affix my signature.

JAMES MILTON ^{his} X ENGLISH.
